TOY

Robert McCall Trexler, Fenton, Mo.

Application October 10, 1936, Serial No. 104,944

1 Claim. (Cl. 46—53)

My invention has relation to improvements in toys and it consists in the novel features of construction more fully set forth in the specification and pointed out in the claim.

5 The principal object of the invention is to provide a toy that will spin and gyrate under the influence of air currents, for which reason the figure constituting the primary element of the toy may, if desired, appropriately be a bird, airplane or other flying object.

A further object of the invention is to provide a toy that may withstand the atmospheric elements so that it may also be adapted for advertising purposes.

15 These objects, together with their manner of accomplishment, will be better apparent from a detailed description of the invention in connection with the accompanying drawing, in which:

Figure 1 represents a top plan of a toy embodying my invention; Fig. 2 represents a side elevation thereof; Fig. 3 represents a vertical sectional detail through the bearing that supports the movable figure, said section taken on a plane represented by the line 3—3 in Fig. 1; 25 and Fig. 4 is a modified form of toy showing that the principal figure may be in the form to represent any desired object.

Referring to the drawing, 1 represents a suitable supporting standard fixed in a suitable base 2 and having a supporting flange 3 near its upper end, which flange is provided with an upper convex surface 4 on which rests a suitable anti-friction bearing 5 secured by screws 6, 6 to a cross member 7 rigidly secured to the principal figure 8 of the toy. The supporting standard 1 has a screw-threaded stem 9 extending upwardly beyond the flange 3, and the bearing 5 and member 7 together are provided with a conical opening 10 to receive the stem 9. A nut 11 is screwed over the threaded extremity of stem 9 for the purpose of confining the member 7 together with the associated parts which collectively constitute the movable element of the toy. In the form illustrated in Figures 1 and 2, the 45 principal element of the toy represents a bird and the supporting member 7 comprises the tail thereof. However, as shown in Fig. 4, the sup-

porting element 7' may be independent of the principal element 8', which in this instance is the representation of a Dutch maid.

A rod 12 is fixed at its upper end to the end of the supporting member 7 opposite to that which carries the figure 8 and extends downwardly a considerable distance, having a weight 13 (in the form of a disc or ball) securely fixed to its lower end. The purpose of the weight 13 is to counterbalance the figure 8 and at the same 10 time bring the center of gravity of the entire movable assembly sufficiently below the supporting flange 3 to impart stability to the figure 8 as it rotates or gyrates under the influence of air currents. 15

From the foregoing description it is apparent that my improved toy will rotate freely in any direction on the anti-friction bearing 5 and at the same time may rock or gyrate on the convex surface 4 of the flange 3 on account of the clearance provided by the conical opening 10. The figure 8, together with the associated parts 7 and 13, cannot be separated from the supporting rod 1 because the nut 11 cooperates with the supporting flange 3 to confine the movable assembly in operative position. 20 25

Figure 8, which constitutes the principal object of the toy, is in fact a weathervane as it is so shaped and disposed so as to be readily affected by air currents which will cause it to 30 revolve about the supporting standard 1 and, owing to the looseness of the pivotal connection, the principal object will also dip or rock during said rotation.

Having described my invention, I claim: 35

A toy comprising a supporting standard, a principal object in the form of a weathervane carried by said standard, a supporting member for said principal object, said supporting member forming a part of said object, a depending 40 weight fixed to the end of said supporting member opposite to the object, and a connection between the supporting member and the supporting standard for permitting oscillation and rotation of the principal object. 45

ROBERT McCALL TREXLER.
